UNITED STATES PATENT OFFICE.

ANTON J. KUFAHL, OF WAUSAU, WISCONSIN.

IRONING BOARD.

Application filed September 27, 1926. Serial No. 137,977.

This invention relates to ironing boards.

Objects of this invention are to provide a cabinet type of ironing board so constructed that the board may be easily folded into the cabinet when not in use, and may be easily extended and held in a rigid, convenient position for ironing.

Further objects of this invention are to provide a cabinet type of ironing board or similar member which is so constructed that means are provided for carrying the lower end of the board in an automatic manner while the board is being folded into vertical position, so that there is no sudden drop of the inner end of the board while it is being so moved, but instead in which the inner end is at all times properly supported in a novel and effective manner.

More specifically, this invention has for its objects the provision of a flexible cable or rope so associated with the ironing board and brace therefor, that the rope will support the rear or lower end of the ironing board while it is being folded into an upward and stored position, and to provide means for adjusting the tension of this rope to insure its correct functioning at all times, irrespective of the stretch of the rope.

Embodiments of the invention are shown in the accompanying drawings in which:—

Figure 1 is a vertical sectional view through the cabinet and through a portion of the extended ironing board;

Figure 2 is a somewhat similar view showing the board in a folded or stored position;

Figure 3 is a plan view of the board in an extended position, showing the cabinet in section;

Figure 4 is a view corresponding to Figure 3, with the board removed and with parts in section;

Figure 5 is an enlarged perspective view of the support for one of the braces or uprights;

Figure 6 is an enlarged view of the adjusting means for the cord, showing a part of the transverse brace of the main brace in section;

Figure 7 is a view corresponding to Figure 6, showing a modified form of the adjusting means.

Referring to the drawings, it will be seen that the device comprises a cabinet 1 which is provided with a pair of substantially upright or slightly slanting members 2 of

sheet metal secured to the sidewalls of the cabinet. The upper ends of these members are apertured, as indicated at 3, and receive the screws 4 for the pulleys 5. The lower ends of the members 2 are upturned, as indicated at 6, and are provided with aligned apertures through which a transverse bottom shaft 7 passes. This shaft, it will be noted from Figures 1 and 4, carries the spaced inner ends of the arms of the brace 8, such arms being joined by a transverse member 9, as shown in Figure 4. The outer ends of these arms are joined by a transverse pin 10 which fits within an elongated slot 11 in a bumper or guide block 12. This block 12 is provided with shouldered portions 13 against which the ends of the brace 8 bear when the ironing board 14 is in a horizontal position, as shown in Figures 1 and 4.

This ironing board is rigidly secured to the block intermediate its ends and its inner end is attached to a rope or cable 16. This cable 16, as may be seen from Figures 1 and 4, is threaded through apertures 17 formed in the arms of the brace 8, and is held within the notched end 18 (see Figures 4 and 6) of a tension adjusting screw 19. This screw is threaded through the transverse member 9 of the brace and is provided with an enlarged head 20, so that it may be readily manipulated.

If desired, the adjusting screw may be formed as indicated in Figure 7, in this form of the invention, the adjusting screw 19' is provided with an enlarged head 20' and is threaded through the transverse member 9 in the manner previously described. However, its outer end is swivelly received by a hardwood block 21, which is provided with an aperture 22 adapted to receive the cord or rope 16. Thus, in adjusting this form of screw the rope may remain in place while the screw is rotated.

The ironing board carries a pair of screw eyes 23 at its inner end which, in turn, carry a transverse shaft 24. This shaft is attached to the rope 16, previously mentioned, and thus attaches the rope to the ironing board at the inner end of such board. The shaft projects laterally beyond the ironing board and rides behind the members 2, while the ironing board is being adjusted. When the ironing board is in a horizontal position, the shaft snaps into the notches 25 in the members 2, as shown most clearly in Figure 5. Thus the inner end of the ironing board

is locked against upward or downward motion, and the action of the outwardly pressing brace 8 holds the shaft seated within the notches.

5 In storing the ironing board, it is necessary to first press it rearwardly a slight distance while it is rocked upwardly slightly. This causes the disengagement of the shaft from the notches 25, and permits the lowering of the inner end of the ironing board while the shaft is guided behind the upright members 2. As the lower end of the ironing board descends, it is supported by the cable 16, and is prevented from dropping suddenly downwardly and damaging either itself or the cabinet, as is frequently the case with the usual types of cabinet ironing boards.

10 It will be seen that the supporting of the rear end of the ironing board while it is being moved into stored position is accomplished without the use of counterweights or springs but automatically by the mechanism described above. The exact tension of the 15 supporting cord or cable can be maintained by proper adjustment of the screw 19 or 19'.

15 It will be seen further that the device is very compact and may be readily placed within the usual depth cabinet.

20 It is to be noted further that the device is of eminently practical construction and also may be cheaply produced.

25 Although the invention has been described in considerable detail, such description is intended as illustrative rather than limiting as the invention may be variously embodied and as the scope of such invention is to be determined as claimed.

30 I claim:

35 1. A cabinet ironing board comprising a receiving cabinet adapted for vertical positioning, a pair of members secured to the sides of the cabinet having pulleys adjacent their upper ends and notches formed near said pulleys, a brace pivotally mounted in the lower ends of said members and adapted to extend outwardly, an ironing board having projecting trunnions adapted to be guided by said members and adapted to fit 40 in said notches when said ironing board is in a horizontal position, means pivotally and slidably joining the outer ends of said brace and said ironing board, and a cable connected to said brace and passing over

45 said pulleys and connected to the inner end 55 of said ironing board.

50 2. The combination of a vertical cabinet, a pair of members positioned within said cabinet and having notches formed therein, a brace having its inner end pivotally supported within said cabinet, an ironing board pivotally and slidably joined to the outer end of said brace and having its inner end provided with projections adapted to fit into 55 said notches, guiding pulleys mounted on opposite sides of said ironing board and located within said cabinet, a cable passing over said pulleys and secured to said brace and to the inner end of said ironing board.

55 3. The combination of a vertical cabinet, a pair of members positioned within said cabinet and having notches formed therein, a brace having its inner end pivotally supported within said cabinet, an ironing board pivotally and slidably joined to the outer 60 end of said brace and having its inner end provided with projections adapted to fit into said notches, guiding pulleys mounted on opposite sides of said ironing board and located within said cabinet, a cable passing over said pulleys and secured to said brace and to the inner end of said ironing board, and means for adjusting the tension of said 65 cable.

70 4. An ironing board comprising a vertical cabinet having members secured to its sidewalls adjacent its lower end and provided with notches, pulleys mounted within said cabinet adjacent the sidewalls thereof, a brace having its inner end pivotally 75 mounted adjacent the lower end of said cabinet, an ironing board having a sliding and pivotal connection with the outer end of said brace, a cable having its ends joined to the inner end of said ironing board and 80 passing over said pulleys, said cable being threaded through apertures formed in said brace, a screw carried by said brace and bearing against said cable to tension said cable, and projecting members carried by 85 said ironing board and adapted to enter said notches when said ironing board is in a horizontal position.

90 In testimony that I claim the foregoing I have hereunto set my hand at Wausau, in the county of Marathon and State of Wisconsin.

105 ANTON J. KUFAHL.
